UNITED STATES PATENT OFFICE

ALVIN S. JOHNSON, OF CHICAGO, ILLINOIS, ASSIGNOR TO RICHARDSON CORPORATION,
OF ROCHESTER, NEW YORK, A CORPORATION OF NEW YORK

DESIGN FOR A BEVERAGE DISPENSER

Application filed October 25, 1930. Serial No. 37,389. Term of patent 14 years.

To all whom it may concern:

Be it known that I, ALVIN S. JOHNSON, a citizen of the United States of America, residing at Chicago, in the county of Cook and State of Illinois, have invented a new, original, and ornamental Design for Beverage Dispenser, of which the following is a specification, reference being had to the accompanying drawing, forming a part thereof.

The figure of the drawings is a perspective view of a beverage dispenser, the opposite or rear side of the dispenser having substantially the same appearance except that it has a dispensing faucet projecting therefrom.

I claim:

The ornamental design for a beverage dispenser, as shown and described.

ALVIN S. JOHNSON.
